UNITED STATES PATENT OFFICE

150,492

DESIGN FOR A LADY'S SLIP

Harold Caplin, New York, N. Y., assignor to Seamprufe, Incorporated, New York, N. Y., a corporation of New York

Application February 4, 1947, Serial No. 136,674

Term of patent 7 years

(Cl. D3—26)

To all whom it may concern:

Be it known that I, Harold Caplin, a citizen of the United States, and a resident of the county of Queens, city and State of New York, have invented a new, original, and ornamental Design for a Lady's Slip, of which the following is a specification, reference being had to the accompanying drawing, forming part thereof, in which:

Fig. 1 is a front view of a lady's slip embodying my design.

Fig. 2 is a rear view of the same.

I claim:

The ornamental design for a lady's slip, as shown.

HAROLD CAPLIN.
